UNITED STATES PATENT OFFICE.

JOHN J. BURGESS AND SAMUEL P. BURGESS, OF ROCK ISLAND, ILLINOIS.

DESIGN FOR A GRILL.

40,291.

Specification for Design.

Patented Oct. 12, 1909.

Application filed July 23, 1909. Serial No. 509,233. Term of patent 7 years.

To all whom it may concern:

Be it known that we, JOHN J. BURGESS and SAMUEL P. BURGESS, citizens of the United States, residing at Rock Island, in the county of Rock Island and State of Illinois, have invented and produced a new, original, and ornamental Design for Grills, of which the following is a specification, reference being had to the accompanying drawing, forming a part thereof.

Figure 1 shows a grill in front elevation and Fig. 2 shows the grill in end elevation.

The general effect of the grill is an elongated panel, the front of which is bulged at a little distance from the edge as indicated at 1, such bulging taking place in a plurality of strips joining the outer border 2 of the grill with an inner border 3. The inner border 3 is divided into a plurality of panels,

the center panel being substantially square and inclosing a circle 4, and within the circle 4 a conventional flower 5. Upon each side of the central panel is a panel inclosing a conventional sunburst 6. Upon opposite sides of the panels so inclosing the sunburst are elongated panels inclosing diamond-shaped figures 7 with other panels upon opposite sides of the last-mentioned panels similarly inclosing conventional sunbursts.

We claim—

The ornamental design for a grill, as shown and described.

JOHN J. BURGESS.
SAMUEL P. BURGESS.
